UNITED STATES PATENT OFFICE.

ROBERT V. MORSE, OF ITHACA, NEW YORK.

TURBO-GENERATOR FOR SHIPS.

1,225,992.

Specification of Letters Patent. Patented May 15, 1917.

Application filed April 5, 1915. Serial No. 19,349.

To all whom it may concern:

Be it known that I, ROBERT V. MORSE, a citizen of the United States, residing at Ithaca, in the county of Tompkins and State 5 of New York, have invented a new and useful Turbo-Generator for Ships, of which the following, taken with the accompanying drawings, is a specification.

My invention relates to the electrical propulsion of ships and in particular to the mounting of the turbo-generators on shipboard in such a manner as to obtain a desirable gyroscopic effect, whereby the ship may be stabilized, or the motion of the ship 15 controlled. The powerful effect of gyroscopes on ships is well known, and the particular object of my invention is to provide a simple mounting for the turbo-generators to obtain a gyroscopic effect; to lead steam 20 to and from the turbine; and to adapt the gyroscopic turbo-generator to a precise precession control.

In the drawings, Figure 1 is an elevation partly in section illustrating my gyroscopic 25 turbo-generator as installed in a ship; Fig. 2 is a transverse cross-section on the line 2—2 of Fig. 1.

Referring to the drawing, 1, 1, 1, designates the frame or decks of a ship. The 30 brackets or braces 2 may also be considered part of the ship structure as they are rigidly secured thereto. Fixed to the braces 2 is the collar 3, which is shown broken away and in section in the drawing. This collar 35 3 surrounds the steam-pipe 4, (shown partly in section), which leads the steam from the boilers of the ship. The steam-pipe 4 is firmly secured to the collar 3, with suitable steam-tight joints. The collar 3 also surrounds 40 the trunnion 5 of the main frame 6, which carries the turbine 7 and the generator 8 rigidly secured thereto. More than one turbine or more than one generator might be mounted in a single 45 frame if desired. The trunnion 5 on which the main frame 6 swings, is made hollow so as to provide a conduit 9 communicating with the steam-pipe 4, from which the steam 50 may be led through suitable pipes or passages to the nozzles of the turbine 7. The steam joints at the trunnion 5 are made steam-tight with suitable packings and rings, arranged to permit the trunnion to turn freely in its socket. The bearings 55 supporting the rotating parts of the turbine 7 and generator 8 are firmly and

strongly supported by the main frame 6, which is strongly built to resist the gyroscopic stresses. Leading from the generator 8 are the conductors 11 connected 60 to the slip rings 12, on which bear the brushes 13, connected to the conductors 14, through which means the current is led to and from the generator irrespective of the position into which it may swing. The 65 lower trunnion 15 of the main frame 6 is larger than the trunnion 5, and rotates in the collar 16 which surrounds it, (shown partly broken away in section), and which is secured to the ship structure 1. The trunnion 15 is made hollow, to provide the conduit 17, in the manner of the other trunnion. The conduit 17 communicates with the exhaust side of the turbine casing 7 and affords a passage through which the expanded exhaust steam may flow, and for that reason is made larger than the conduit 9 in the trunnion 5, to accommodate the increased volume of steam. The joint at the 70 trunnion 15 is provided with suitable packing which renders it steam-tight and air-tight, while permitting the trunnion to turn in its socket. The conduit 17 communicates with the exhaust pipe 18, which is secured to the fixed collar 16. The pipe 18 may lead 75 to the condenser of the ship. Connected to the main frame 6 is the connecting rod or link 20 which connects the main frame 6 with a precession engine or brake 23, whereby the precession is determined and controlled. This precession engine or brake 23 is diagrammatically shown as a steam or 80 hydraulic cylinder 24, whose valves are controlled electrically through the wires 25 by the inverted pendulum 26, which is operated 85 manually or by the motion of the ship, to make and break the controlling circuit. The particular form of precession controller is immaterial and any of the precession engines or controllers used with the ordinary 90 ships' gyroscopes may be used with this turbo-generator mounting, since no condenser or other bulky part need be swung. The precession controlling means need not necessarily be connected by a link; since 95 100 gearing, cables, friction brakes, or any other external means might be employed. An emergency brake 21 is provided so that in case of derangement of the regular precession controlling means the main frame 6 105 may be controlled in its swing or may be locked. This is necessary since unlike the 110

ordinary ships' gyroscope the rotor may not be stopped in case of derangement without stopping the ship.

The operation is as follows: The turbo-generator 7, 8, may be mounted with its axis horizontal, and with the trunnion axis of the main frame 6 vertical. To control the rolling of the vessel the turbo-generator axis would lie in general transverse of the ship. Then to create gyroscopic torques transverse of the ship, as for rolling, the ends of the frame 6,—as where the link 20 is attached,—should be moved or precessed forward and back, or fore-and-aft of the ship. That is, the trunnion axis and the rotor axis should both be at right angles to the axis about which the gyroscopic torque is to be created, or the axis of the ship's motion. As the main frame 6 is thus swung forward and back the steam may flow freely through the trunnion 5 and the trunnion 15 as indicated by the arrows, thus operating the turbine 7. In case of emergency the precession of the main frame 6 may be prevented or controlled through the brake 21. This brake or lock may be mechanical, magnetic, or of any other powerful type.

While the turbo-generator axis will preferably lie horizontal and the trunnion axis vertical, because of the firm foundation furnished by the large exhaust trunnion 15, yet the set may be arranged at any angle,—provided the rotor and trunnion axes lie in a plane at right angles to the axis of the ship's motion. Thus for example the turbo-generator axis may be arranged vertically and the trunnion axis horizontally athwartships, as if for example the drawing were turned through 90°, so that the steam would come in at the side through the small trunnion and out from the other side through the large trunnion. The same precise control of precession is possible in this position as in the first mentioned position, since the bulky condenser is outside of the gyroscopic system and hence the swinging or precessing parts are readily controlled. It should also be understood that several units such as illustrated may be connected together, so as to precess together.

I claim as my invention,

1. A gyroscopic mounting for ships' generators comprising in combination a main frame, a turbo-generator secured to said frame, a hollow trunnion through which steam may enter to the turbo-generator, a second hollow trunnion through which expanded uncondensed exhaust steam may exhaust from the turbo-generator, the main frame being mounted to swing upon said hollow trunnions, and means for controlling said swing.

2. A gyroscopic mounting for ships' generators, comprising in combination a steam turbine mounted with its axis in a substan-

tially horizontal position, trunnions pivotally supporting said turbine, the trunnions being arranged in a substantially vertical position, and means for conducting steam to said turbine.

3. A gyroscopic mounting for ships' turbines, comprising in combination a turbine, trunnions supporting said turbine to permit swinging movements thereof, one of said trunnions having an intake passage, one of said trunnions having an exhaust passage, the exhaust passage being sufficiently larger than the intake passage to allow expanded uncondensed exhaust steam to flow freely through the exhaust passage.

4. A gyroscopic mounting for ships' turbines, comprising in combination a turbine, trunnions supporting said turbine to permit swinging movements thereof, one of said trunnions having an intake passage, one of said trunnions having an exhaust passage, the exhaust passage being sufficiently larger than the intake passage to allow expanded uncondensed exhaust steam to flow freely through the exhaust passage, and means for controlling the swinging movements of the turbine.

5. In a gyroscopic mounting for ships' turbines, the combination of a turbo-generator mounted for swinging movements relative to a ship, means for conducting the motive fluid to the turbo-generator, means for conducting the electric current from the turbo-generator, and means for locking the turbo-generator against swinging movements relative to the ship.

6. In a gyroscopic mounting for ships' turbines, the combination of a turbo-generator mounted for swinging movements relative to a ship, means for conducting the motive fluid to the turbo-generator, means for conducting the electric current from the turbo-generator, and mechanical means for creating precessional movements of the turbo-generator.

7. In a gyroscopic mounting for a ship's turbo-generator, the combination of a turbo-generator, pivotal mountings for said turbo-generator on which it is adapted to swing, one of said pivotal mountings being larger than the other, means for taking the working fluid into the turbo-generator, means for taking the expanded exhaust working fluid from the turbo-generator out through the larger pivotal mounting, and means for conducting the electric current from the turbo-generator.

8. In a gyroscopic mounting for a ship's turbo-generator, the combination of a turbo-generator, pivotal mountings for said turbo-generator on which it is adapted to swing, one of said pivotal mountings being larger than the other, means for taking the working fluid into the turbo-generator, means for taking the expanded exhaust working fluid

from the turbo-generator out through the larger pivotal mounting, means for conducting the electric current from the turbo-generator, and mechanical means for determining and controlling the swinging movements of the turbo-generator.

9. In a gyroscopic mounting for ships' turbines, the combination of a steam turbine, a trunnion mounting for the steam turbine to permit swinging movements thereof, means for conducting steam into said turbine, a condenser, means for conducting exhaust steam from the turbine out through the trunnion mounting to the condenser, whereby the turbine may have swinging movements relative to the condenser.

10. In a marine power plant, a turbo-generator mounted for precessional movements so as to constitute a gyroscopic system, a fixed condenser external to said gyroscopic system, and a hollow trunnion through which exhaust steam may flow from the turbo-generator to the condenser.

11. In a gyroscopic mounting for ships' turbines, the combination of a turbo-generator, hollow pivotal mountings for said

generator on which it is adapted to swing, and means for creating and controlling the swinging movements of the turbo-generator.

12. In a gyroscopic mounting for ships' turbines, the combination of a turbo-generator, hollow pivotal mountings for the turbo-generator on which it is adapted to swing, and means for conducting the uncondensed working fluid to and from the turbo- 30 generator by way of the pivotal mountings.

13. In a gyroscopic mounting for ships' turbines, the combination of a turbo-generator mounted for precessional movements, means for conducting the uncondensed working fluid to and from the turbine, means for conducting the electric current to and from the generator, and means for restraining the precessional movements of the turbo-generator. 40

In witness whereof I have hereunto set my hand this 5th day of April, 1915.

ROBERT V. MORSE.
